ATTORNEY

UNITED STATES PATENT OFFICE.

JOSEPH BOENING, OF SCOTT, SASKATCHEWAN, CANADA.

FOLDING TENNIS RACKET.

Application filed November 30, 1927. Serial No. 236,763.

This invention relates to improvements in tennis rackets and which embodies among other characteristics a handle foldably mounted thereon.

5 Another object of the invention comprehends gripping portions carried by the handle adapted for engagement with the racket proper.

A further object of the invention contemplates a coiled spring adapted to provide a racket frame.

More specifically stated wires are stretched from the coiled spring, rather than strands of gut which can not be used during 15 inclement weather.

With the above and other objects in view, the invention further consists of the following novel features and details of construction, to be hereinafter more fully described, 20 illustrated in the accompanying drawings and pointed out in the appended claims.

In the drawing:

Figure 1 is an elevation of the invention.

Figure 2 is a sectional view taken on line 25 2-2 of Figure 1.

Figure 3 is a detail view of the hingedly connected end of the handle member.

Figure 4 is a fragmentary elevation of one 30 of the sections of the handle member.

Figure 5 is a longitudinal sectional view taken through the connecting portion of the sectional handle member.

Referring to the drawing in detail, wherein like characters of reference denote cor- 35 responding parts, the reference characters 10 and 11 indicate complementary handle sections which, as shown, are semi-circular in cross section and which when positioned for active use have the side edges thereof

40 lying flush with the side edges of the companion section to provide a cylindrical handle member. Each of the sections being provided with depressions or pockets 12 and 13 respectively; the pocket 12 being tapered 45 to accommodate the head of a bolt member 14 whereas the depression or pocket portion 13 is cylindrical to accommodate and permit rotation of a nut member 15 carried upon the tapped end of the bolt member 14. The

50 bolt member is disposed adjacent the butt end of the completed handle. The sections 10 and 11, as best illustrated in Figure 2 of the drawing, are tapered inwardly toward the uppermost end thereof and which terminate to provide horizontally disposed semi-circular sleeve portions 16 which are adapt-

ed to receive through openings 17 in the side walls thereof, a bolt member 18, the purpose of which will be presently apparent.

The frame for the racket is preferably 60 composed of a coiled spring 19 of a comparatively heavy gauge. A shaft 20 extended within the ends of the spring 19 is adapted to be positioned between the semi-circular sleeve members 16 and adapted to 65 receive the bolt member 18 therethrough. The bolt member 18 when tightened will not only prevent displacement of the shaft 20 but which will also cause the semi-circular sleeve portions 16 to rigidly engage the portions of the spring member 19 therebetween and against said shaft.

Instead of stretching gut or other strings upon the racket frame or frame member 19, I have employed wires 21 which will permit use of the racket without injury during 70 inclement or adverse weather conditions.

The improved type of racket may be manufactured in great numbers and sold at nominal cost, due to the fact that the seasoning of lumber employed for making the 80 frames is obviated as well as the costly and constant restrunging of rackets with gut and other preparations.

It is to be noted that by loosening the 85 bolt member 18, and removal of the bolt 14, the entire handle member, composed of the sections 10 and 11 may be folded upon the racket frame or be entirely removed therefrom when it is desired to store or carry 90 the same, inasmuch as the sleeve portions will be free to pivot about the shaft 20 to occupy the dotted line position as illustrated in Figure 1 of the drawing.

The invention is susceptible of various 95 changes in its form, proportions and minor details of construction, and the right is herein reserved to make such changes as properly fall within the scope of the appended claims.

Having described the invention, what is claimed is:—

1. A racket comprising a frame, wholly composed of a length of coiled spring, a handle for the racket, and means foldably 105 mounting the handle upon the frame, being adapted to prevent distortion thereof.

2. A tennis racket comprising a frame, said frame being composed of a length of coiled spring, a handle for the racket consisting of companion sections, gripping portions carried by each of the sections being 110

adapted for engagement with said frame, and means for detachably connecting the gripping portions of the handle members with said frame.

5. 3. A tennis racket comprising a frame composed of a length of coiled spring having a matting of wire stretched thereon, a handle member composed of complemental sections, semi-circular sleeve portions horizontally disposed upon the ends of the sections being adapted for registration to provide a gripping portion for said spring, and a shaft having connection with the ends of the spring within the gripping enclosure as defined by the semi-circular sleeve portions.
10. 4. A tennis racket comprising a frame

composed of a length of coiled spring having a matting of wire stretched thereon, a handle member composed of complemental sections, semi-circular sleeve portions horizontally disposed upon the ends of the sections being adapted for registration to provide a gripping portion for said spring, a shaft having connection with the ends of the spring within the gripping enclosure as defined by the semi-circular sleeve portions, and means for detachably connecting and foldably mounting said handle upon the frame.

In testimony whereof I affix my signature.

Rev. JOSEPH BOENING.
